UNITED STATES PATENT OFFICE.

FRANK H. WOOLF, OF CHICAGO, ILLINOIS.

COATING MACHINE.

Application filed February 3, 1920. Serial No. 355,996.

To all whom it may concern:

Be it known that I, FRANK H. WOOLF, a citizen of the United States, residing at Chicago, in the county of Cook and State of Illinois, have invented certain new and useful Improvements in a Coating Machine, of which the following is a description.

My invention relates to that general class of devices known as coating machines for covering confections, nuts, or other articles, with chocolate or the like. The invention has among its objects the production of a simple, compact, convenient, durable, efficient, and reliable device of the kind described, wherein the articles to be coated are suitably separately coated and thereafter discharged, ready for packing and shipment if desired. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Figure 1 is a side elevation of the preferred type of machine, and

Figure 2 is substantially a vertical section through a portion of the same, enlarged to more clearly show the construction.

Referring to the drawings, 1 represents a frame of the desired size, style and material provided with suitable substantially parallel and vertical side members, 2, and 3, at their tops, adapted to form the side walls of an enclosure or casing. A plurality of rolls 4, 6, 8 and 10 are rotatably mounted in suitable bearings carried by the side members 2 and 3 respectively. There is also provided a plurality of bars 5, 7 and 9, or the equivalent, which are carried by the side members. The bars or the rolls may be fixed or adjustable if desired. Ordinarily I prefer to make the bearings for roll 4 fixed and make the bearings for the rolls 6 and 8 vertically adjustable. It is considered unnecessary to describe the adjustable bearings in detail, as this may be of any of the well known types. The bars 5, 7 and 9 may be made so that they may be adjusted substantially horizontally. I have shown adjusting bolts 46 and 47 for bars 7 and 9 respectively. A reticu-

lated belt 11, or carrier, preferably formed of woven wire or the equivalent, is mounted upon the roll 4 and bar 5 and arranged to be driven by the roll, the same serving as a conveying belt. Similar belts or carriers 12 and 13 are mounted on roll 6 and bar 7 and roll 8 and bar 9 respectively. The articles to be coated may be discharged or placed on the belt 11 in any desired manner. For purposes of illustration, I have shown movable members 16. These, however, form no part of the present invention and need not be described in detail herein.

Any suitable means may be provided for coating the articles carried by the belt 11. As shown, 17 is a container adjustably carried on the brackets 18, the container having an open side provided with an adjustable wall 19, which is preferably hinged as at 20. The container may be moved or adjusted backward or forward over the belt 11 and if so desired, may be held in its adjusted position on the guides 18 by suitable bolts 72 or the like. The position of the wall 19 is regulated by the desired number of adjustable bolts or screws 22, carried in bar 21, extending across the machine, or by equivalent means for the purpose. The weight of the contained material tends to move the side or wall 19 to its open position so that the coating material will be discharged as indicated by the arrow in Figure 2. In the construction shown, I provide a tank or container 26, which may be supported upon the frame 1 of the machine and which preferably has a jacket 27 so as to provide a space 28 for containing hot water, steam, or other suitable medium for controlling the temperature of the material in the tank. A pipe 23, connected with pipe 23', communicating with the tank, is arranged to discharge the coating material into the receptacle 17, the same being elevated by means of pump P, shown in Figure 1, or the equivalent means for the purpose. The pipe 23 is preferably provided with a discharge pipe 24 extending above the receptacle 17 and having openings 25 through which the material flows into the receptacle 17, from whence it is discharged to coat the articles carried by belt 11. Arranged at the end of the belt 11, adjacent the belt 12, is a plate or apron 31, or its equivalent, which extends across the machine and is preferably adjustably, as shown pivotally, supported on a rod or bar 32. Any suitable means may be provided for controlling the

position of the apron 31, that shown consisting of a rock shaft 33, having cams thereon adapted to engage the apron, the shaft being controlled by an arm 30 or its equivalent, 5 extending to a convenient point for operating, for example, to the exterior of the side wall 3 or 2, as may be desired. I also provide an apron 35 arranged below the upper portion of belt 11, the same being supported 10 at 36 and arranged to be controlled by a shaft 37, cams 38 and operating handle 39 or equivalent means for the purpose. A similar apron 41 may also be provided for the belt 12. As shown, this is adjustably supported at 42 and controlled by shaft 43, 15 cams 45 and operating arm 44. The tension on the belts 12 and 13 may be controlled by the adjusting screws 46 and 47, or equivalent means for the purpose, it being preferred to 20 keep these belts tightened sufficiently so that they do not sag to any extent under the weight of the articles carried thereby. I have shown a belt 48 arranged over a roll 49 and upon which material from belt 13 is 25 discharged. In the particular construction shown, belt 48 extends to a desired point sufficiently far from the machine to permit the coating to harden and if desired, which is generally the case, the same may extend 30 through a cold or refrigerating chamber to facilitate the hardening and improve the product. At the extreme end of belt 48 which, as mentioned, may be of the desired length or be supplemented by cooperating 35 belts, I provide a discharge belt 51 arranged adjacent the packing table 52.

Any suitable mechanism may be employed 40 for driving the several belts and other parts. In Figure 1, I have shown a series of sprock- 45 ets and chains by means of which power is transmitted from a driving belt 55, or the equivalent, to a driving belt 54, which drives sprockets 56 and 56' on shaft 53, which is arranged to drive the roll or pulley 4. Roll 50 or pulley 6 is driven by sprocket 58 and chain 57 and roll or pulley 8 through shaft 61 from pulley 62 and chain 60. Roll 10 connected with shaft 66, is driven from shaft 61 through sprocket 63 and chain 64 and roll 49, which is connected with shaft 68 55 from chain 67 through sprocket 71. This is also arranged to drive sprocket 58, which, in turn, may drive chains 69 and 70 through suitable sprocket mechanism and move the various carriers.

In operation the articles to be coated are placed or discharged on the comparatively slow moving belt 11 which carries them 60 through the coating material discharged from the tank 17, the material spreading on the belt 11 the apron 35 being adjustable for regulating the amount of material passing through the reticulated belt 11. The coated articles are discharged onto apron 31 and 65 from thence on to the belt 12, apron 41 con-

trolling the discharge of the material through belt 12. I have found from experience that by adjusting the position of the apron 31, I can regulate the amount of the coating material retained by and on the articles. If the same is as shown in Figure 2, a coating will be applied to the material or articles, which coat will be increased in thickness if the free end of the apron is raised. The raising of the apron tends to 70 retard the flow of the coating material, which is in a liquid state, usually semi-fluid, but flows slowly, owing to its thickness or consistency. When the apron is depressed, the flow of the material and articles down 75 the apron seems to be accelerated, resulting in a thinner coat. As the articles are carried on the belt 12, a portion of the coating material may flow through the belt and back 80 into the container 26, the thickness on the bottom of the articles being regulated to a large extent by the apron 41. After passing along on the belt 12, which moves at a somewhat greater speed than the belt 11, the same passes over the rotating shaft or bar 85 10 and so upon the belt 13. The roll or shaft 10 travels at a greater surface speed than the belt, so that the same are to some extent thrown on the belt 13, which in turn moves somewhat faster than belt 12. The roll 10, traveling at a surface speed faster than the belt 12 and being above the belt 13, engages the coated articles, whereby it draws the coating into a ridge at the line of contact therewith and strings it out as it throws the articles onto the belt 13, thus producing what may be termed a string of coating on the articles, giving the same appearance to them as if they had been hand-dipped. After 90 passing on the belt or carrier 13, the same are carried along and discharged on the belt 48 and carried to the discharging end or adjacent table 52. Any surplus material from the belt 13 may flow into the receptacle 50, which may be piped back into the receptacle 95 or tank 26 in any suitable manner. The machine described efficiently and evenly coats the articles and may be adjusted to give just the coating desired. The same 100 operates and produces a machine coated article resembling the hand-dipped article, thereby adding to the attractiveness of the product, but reducing the cost of manufacture.

Having thus described my invention, it is 105 obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a coating machine, a receptacle ex- 110

- tending transversely across said machine having a slot adjacent its bottom for discharging a substantially uniform curtain of coating material from said receptacle, means 5 for adjustably supporting said receptacle longitudinally of said machine, in combination with a carrier extending longitudinally of said machine below said receptacle and a second carrier extending from below said 10 first carrier longitudinally of said machine and adapted to receive material from said first carrier roller traveling at a higher speed than said second carrier at the discharge end thereof and adapted to receive 15 the coated articles therefrom and a third carrier extending from below said second carrier and roller, and means for driving said carriers.
2. In a coating machine, a receptacle extending transversely across said machine having a slot adjacent its bottom for discharging a substantially uniform curtain of coating material from said receptacle, means for adjustably supporting said receptacle 20 longitudinally of said machine, in combination with a carrier extending longitudinally of said machine below said receptacle and a second carrier extending from below said first carrier longitudinally of said machine 25 and adapted to receive material from said first carrier, a roll arranged at the end of the second carrier and a third carrier extending from below said second carrier and roll and arranged to receive the material 30 from said roll and second carrier, and means 35 for driving said carriers and roll.
3. In a coating machine, a receptacle extending transversely across said machine having a slot adjacent its bottom for discharging a substantially uniform curtain of coating material from said receptacle, in combination with a reticulated carrier extending longitudinally of said machine below said receptacle and a second carrier extending 40 from below said first carrier longitudinally of said machine and adapted to receive material from said first carrier, a rotatable member arranged at the discharge end of the second carrier substantially flush 45 with the top face thereof, and means for receiving the material discharged over said member.
4. In a coating machine, a receptacle extending transversely across said machine having a slot adjacent its bottom for discharging a substantially uniform curtain of coating material from said receptacle, in combination with a reticulated carrier extending longitudinally of said machine below 50 said receptacle and a second carrier extending from below said first carrier longitudinally of said machine and adapted to receive material from said first carrier, a rotatable member arranged at the discharge 55 end of the second carrier substantially flush with the top face thereof, and means for receiving the material discharged over said member.
5. In a coating machine, a receptacle extending transversely across said machine having a slot adjacent in its bottom for discharging a substantially uniform curtain of coating material from said receptacle, in combination with a carrier extending longitudinally of said machine below said receptacle, an apron arranged below the top side of the carrier and a second carrier extending from below said first carrier longitudinally of said machine and adapted to receive material from said first carrier, an apron arranged below the top side of the second carrier, a receiving carrier, means at the end of said second carrier for distributing articles discharged from said second carrier.
6. In a coating machine, a receptacle extending transversely across said machine having a slot adjacent in its bottom for discharging a substantially uniform curtain of coating material from said receptacle, in combination with a carrier extending longitudinally of said machine below said receptacle, an adjustable apron arranged below the top side of the carrier and an apron arranged at the discharge end of said first carrier, a second carrier extending from below said first carrier longitudinally of said machine and adapted to receive material from said first carrier, an adjustable apron arranged below the top side of the second carrier, a receiving carrier, means at the end of said second carrier for distributing articles discharged from said second carrier.
7. In a coating machine of the kind described and in combination, a receptacle extending transversely across said machine having a slot adjacent its bottom for discharging a substantially uniform curtain of coating material from said receptacle, a carrier extending longitudinally below said receptacle and a second carrier extending from below said first carrier longitudinally of said machine and adapted to receive material from said first carrier, a roller positioned near the end of the first carrier and means for rotating said roller at a surface speed greater than said carrier for distributing articles upon said second carrier and means for adjusting said carriers to control the distance between said carriers.
8. In a coating machine and in combination, a receptacle extending transversely across said machine having a slot adjacent its bottom for discharging a substantially uniform curtain of coating material from said receptacle, a carrier extending longitudinally of said machine below said receptacle, a second carrier extending from below said first carrier longitudinally of said machine and adapted to receive material from said second carrier.

terial therefrom, and means mounted below the carrying surface of said carriers for adjustably controlling the amount of coating material upon the surfaces thereof.

5 9. In a coating machine and in combination, a receptacle extending transversely across said machine having a slot adjacent its bottom for discharging a substantially uniform curtain of coating material from 10 said receptacle, a carrier extending longitudinally of said machine below said receptacle, an apron arranged at the discharge end of said carrier, a second carrier extending from below said first carrier longitudinally 15 of said machine and adapted to receive material from said apron, an apron mounted below the carrying surface of said carriers for controlling the amount of coating material upon the surfaces thereof, and means 20 for adjusting said second apron to control the discharge of material thereover.

10. In a coating machine, a receptacle extending transversely across said machine having a slot in its bottom for discharging 25 a substantially uniform curtain of coating material from said receptacle, in combination with a carrier extending longitudinally of said machine below said receptacle and a second carrier extending from below said 30 first carrier longitudinally of said machine and adapted to receive material from said first carrier, an apron adjustably mounted below the carrying surfaces of said carriers for adjustably controlling the amount of 35 coating material upon said surface and means for adjusting said second carrier to control the distance between said carriers.

11. In a coating machine, a receptacle extending transversely across said machine 40 having a slot in its bottom for discharging a substantially uniform curtain of coating material from said receptacle, in combination with a carrier extending longitudinally of said machine below said receptacle, means 45 for placing articles upon said carrier and a second carrier extending from below said first carrier longitudinally of said machine and adapted to receive material from said first carrier and means independently of

said discharge slot for adjustably controlling 50 the amount of coating material on said carriers.

12. In a coating machine and in combination, a receptacle extending transversely across said machine having a slot in its side 55 adjacent its bottom for discharging a substantially uniform curtain of coating material from said receptacle, means for controlling the width of said slot, means for adjustably supporting said receptacle, a carrier extending longitudinally of said machine below said receptacle and a second carrier extending from below said first carrier longitudinally of said machine and adapted to receive material from said first 60 carrier, means mounted below the carrying surface of said carriers for adjustably controlling the amount of coating material upon the surfaces thereof and means for controlling the material on said carriers. 70

13. In a coating machine and in combination, a receptacle extending transversely across said machine having a slot adjacent its bottom for discharging a substantially uniform curtain of coating material from 75 said receptacle, means for controlling the width of said opening, means for adjustably supporting said receptacle longitudinally of said machine, a carrier extending longitudinally of said machine below said receptacle, 80 means for placing articles upon said carrier and a second carrier extending from below said first carrier longitudinally of said machine and adapted to receive material from said first carrier, means at the 85 end of said second carrier for distributing articles discharged from said second carrier and means for driving said carriers and distributing means at predetermined relative speeds. 90

In testimony whereof, I have hereunto signed my name in the presence of two subscribing witnesses.

FRANK H. WOOLF.

BERTHA HARTMANN.

Certificate of Correction.

It is hereby certified that in Letters Patent No. 1,460,189, granted June 26, 1923, upon the application of Frank H. Woolf, of Chicago, Illinois, for an improvement in "Coating Machines," errors appear in the printed specification requiring correction as follows: Page 3, line 12, after the word "carrier" insert a comma, and insert the article *a* before the word "roller"; and that the said Letters Patent should be read with these corrections therein that the same may conform to the record of the case in the Patent Office.

Signed and sealed this 14th day of August, A. D., 1923.

[SEAL.]

KARL FENNING,
Acting Commissioner of Patents.
